UNITED STATES PATENT OFFICE.

WILBERT H. MORGAN, OF BROOKLYN, NEW YORK.

DRIER FOR PHOTOGRAPHIC PRINTS.

Application filed April 20, 1922. Serial No. 555,725.

To all whom it may concern:

Be it known that I, WILBERT H. MORGAN, a citizen of the Dominion of Canada, residing in Brooklyn, in the county of Kings and 5 State of New York, have invented certain new and useful Improvements in Driers for Photographic Prints, of which the following is a specification.

This invention relates particularly to machines for drying prints, such as photographic prints, blue prints, and the like, but some features of my invention may be embodied in drying machines of other kinds. In my United States Patent No. 1,250,618 of 10 Dec. 18, 1917, I have shown a machine for drying photographic prints in which two heated drums are arranged side by side and are traversed by two superimposed belts or webs which hold the prints between them and 15 carry the prints around portions of the drums. The belts are guided by adjustable guide rollers and means is provided for adjustable imparting a suitable tension to the belts. I have found that superior results are 20 obtained by arranging the heated drums a short distance apart, one above the other, in such manner that the heat from the lower drum assists in heating the upper drum and the portions of the belt and the prints traversing the space between the two drums. I have also found that in view of the length 25 of the belts and the material of which they are made, it is necessary or desirable to provide some means for maintaining the proper alignment of the belts as they pass through 30 the machine. In the machine shown in my former patent, the tension device is so constructed that it may be adjusted by ratchet mechanism but when so adjusted it is rigidly 35 held. I have now found it desirable to have such tension device yieldingly held so that it may automatically adjust itself when required. Inasmuch as photographic prints usually bend or become curved when being 40 dried and as it is desirable that they should be as straight or flat as possible, I have provided means whereby the prints are flattened to the desired extent just prior to their de-

livery to the tray which receives the finished prints.

In carrying out my present invention I employ a frame of any suitable construction, and in the frame I mount one above the other and a short distance apart two drying drums which are heated by gas, gasoline, electricity, or other suitable heating medium. Two superimposed belts are employed as heretofore and they are guided in such manner that at one point in the machine, prints may be fed between them and at another point the prints 55 may be discharged into a suitable tray or receiver. The prints are arranged close together, one belt being superimposed upon the other from the receiving end of the carrier to the delivery end thereof and they pass 60 around portions of the drums in a novel way. The belts are not superimposed throughout 65 their entire lengths, but are separated for a portion of their lengths and are guided in such manner as to return to the feed end of 70 the machine in proper relation.

In order that the desired tension may be imparted to the belts, guide rollers are employed mounted in suitable frames which are held under spring tension and in order to 75 maintain the alignment of the belts I provide devices which operate on the opposite edge portions of the belts in such manner as to correct any tendency which they may have to leave the proper path of traverse through 80 the machine. In order that the belts may have a greater extent of surface applied to the heating drums, I provide novel means for drawing towards each other those portions 85 of the belts disposed between the two drums and which portions of the belts are exposed not only to the heat of the two drums, but also to the drying effects of the atmosphere.

The device for flattening or straightening the prints preferably comprises an adjustable 90 roller which presses against the belts at their delivery end and imparts a curvature thereto of such nature as to bend the prints reversely to their normal bend and thus correct their shape. Other features of the invention will 95 be hereinafter described.

In the accompanying drawings:—

Figure 1 is a side view of a print drying machine embodying my improvements.

Figure 2 is a detail view on an enlarged 5 scale, partly in elevation and partly in section on the line 2—2 of Figure 1 and showing particularly how one of the improved tension devices is constructed and mounted.

Figure 3 is a view on an enlarged scale in 10 side elevation of the devices for guiding the delivery ends of the belts and for correcting the shape of the prints before leaving the belts.

Figure 4 is a detail view on an enlarged 15 scale and in section on the line 4—4 of Figure 1, showing particularly certain features of the devices for preserving the alinement of the belts.

Figure 4 shows the parts in their normal 20 position when the belt is running true.

Figure 5 is a plan view of the parts shown in Figure 4.

Figure 6 is a view similar to Figure 5 but 25 illustrating how the devices operate when the belt tends to leave its normal path.

The main frame of the machine is preferably made for the most part of channel iron but other material may be employed. It consists of four uprights A having feet a, 30 horizontal bottom cross-pieces B connected to the uprights A a short distance above their lower ends and inclined cross-pieces C connected to one set of uprights at the upper ends thereof and to the other set of uprights a considerable distance below their upper ends thus providing means above said inclined cross pieces for supporting the belt driving and print delivery mechanism. Diagonal frame pieces D connected to two of 35 the uprights at their junctions with the cross pieces B are connected to the other set of uprights at their junction with the inclined cross pieces C. This form of frame is strong and durable and is the construction preferred although not essential.

The drums E and F are arranged one above the other with a space between them. They may be constructed in any suitable way and are mounted to turn in bearings in the 50 frame in the manner shown. The ends of the drums are formed with ventilating openings e, f and man holes e', f'. These drums may be heated in any suitable way, preferably by gas or gasoline supplied through 55 pipes G provided with regulating cocks g.

As heretofore I employ two belts which are so supported and operated as to carry the prints to be dried into contact with the drawing drums and to deposit them in a 60 suitable receptacle. The inner belt or the one which comes in direct contact with the drying drums is marked X while the outer belt which holds the prints on the inner belt is marked Y. The inner belt X passes from

a tension roller J over a guide roller K 65 mounted between the cross-pieces C to the upper drum E and presses against the lower side portion thereof on one side. It then passes through a guiding device L located between the drums, then into contact with 70 the lower drum around which it passes being in contact with all but a small portion of the surface thereof. The belt X next passes up through the guide device L into contact with one side of the drum E, then over an adjustable guide roller M, then around a guide roller N, then under the roller o of an alining device O and then to the tension roller J. The outer belt Y passes from a guide roller P at the feed end of the machine over 75 the roller K and follows the inner belt through the guide L around the lower drum F, around the drum E, and across the adjustable roller M, carried by the bracket a². It then passes around another guide roller R 80 and over a roller S to a guide roller T located in the lower part of the frame. It then passes through an alining device U, under a guide roller V, through the tension device W and back to the guide roller P. 85 It will be observed that the guide L, located in the space between the drying drums, holds the belts close to the adjacent portions of the drums and thus increases the heating surface in direct contact with the drums. 90 This device consists of a frame l having rollers l' on opposite sides of the two belts. These rollers extend entirely across the machine and are preferably a little longer than the width of the belts. The frame is held 95 stationary, being attached to the adjacent uprights A.

Separate tension devices are employed for the two belts. It is important that the same degree of tension should be applied to the 100 belts in order that they may properly move together. The tension device for the outer belt Y comprises a frame consisting of side pieces w connected in any suitable way as indicated at w¹⁰ and pivotally mounted on 105 the front uprights A. A roller w² is carried at the lower end of the frame and a roller w³ at the upper end thereof, and the outer belt Y traverses these rollers in the manner indicated. A ratchet wheel w⁴ is keyed to the 110 frame W in the manner indicated at w⁵, Figure 2, and this ratchet wheel is engaged by a spring pawl z carried by an operating lever or handle Z. This handle is connected by a spring Z' with the guide L. The tension of the spring may be regulated by adjusting the handle Z to cause the pawl z to engage different notches in the ratchet wheel. I have found that by equipping the 115 tension device with a spring, the operation of the machine is materially improved.

In order to mount the frame W between the uprights and to support parts of the

mechanism I preferably as shown in Fig. 2 employ stub shafts w' which are secured to the frame bars and have beaded ends as shown. The lever Z is pivotally mounted 5 on one of the stub shafts w' as shown in Fig. 2.

The inner belt is also provided with a tension device. This is shown at I and it comprises a frame carrying the roller J herein- 10 before referred to. This frame is provided at i to the inclined cross-pieces C. Preferably two springs I^2 are employed, one on each side of the machine. Each of these springs carries a hook i^2 which may be made 15 to engage any one of a series of holes c in the inclined frame bar C so that the tension of the springs may be thus varied.

The belts are driven by mechanism operated by motor M^2 which is suitably geared as 20 shown to the shaft r on the roller R. As clearly shown in Figure 3, the belts X and Y separate when they come to the rollers M and R and dry prints are delivered from the belt to a suitable receiving tray S^{10} .

25 Inasmuch as photographic prints have a tendency to curl or bend and as it is desirable that they should be as straight or flat as possible, I provide means for flattening the prints just before they leave the belts. This 30 device consists of a roller M, the shaft m of which is engaged by adjusting screws m' and the shaft is mounted in slotted bearings which permit the roller to be moved diagonally upwards in such manner as to bend the 35 inner and outer belts just before they separate. I have found that by thus bending the belts and the contained prints, the desired flatness is given to the prints before they drop into the receiving tray. Should any 40 of the prints adhere to the outer belt at the delivery ends of the belts, they will be removed therefrom by the doctor D^{10} and dropped into the receiving tray.

45 Experience has demonstrated that where belts, such as those made of canvas, are employed, there is difficulty in machines of this class in causing the belts to move in proper alinement through the machine and it is, of course, important that the belts should thus 50 move while carrying the prints and in order to correct any tendency to move out of alinement, I have provided devices for operating on the inner belt and other devices for operating on the outer belt. The devices for 55 operating on the outer belt are shown at U. They comprise a roller u supported by two links u' which are hinged to the diagonal frame pieces D at d . Each link u' is independently hinged to the frame. The roller 60 u which is shown also in Figures 4, 5 and 6, is preferably partially covered with strips of emery paper, corrugated rubber, or the like as indicated at u^3 . The roller u extends from one side of the machine to the

other as shown in Figures 4, 5 and 6. Co- 65 operating with the roller u are two rollers u^6 , u^7 . These rollers are quite short and they are secured to a shaft u^8 , which extends from one side of the machine to the other and passes through slots u^9 in the links u' . 70 A spring v is attached to each end of the shaft or rod u^8 and to the shaft v' of the roller u . In this way the rollers u^6 , u^7 are drawn towards the roller u and are normally held yieldingly in contact therewith. Fig- 75 ure 4 shows the outer belt Y in proper alinement, passing over the roller u without coming in contact with the tapered ends of the rollers u^6 , u^7 , and when the belt runs normally the parts will occupy the position 80 shown in Figure 4 and also in Figure 5, but should this belt pass out of alinement as indicated in Figure 6, one of its edges will be guided by the tapered roller into the bite of the rollers u and u^6 or u^7 and then the link 85 u' which carries the small roller thus engaged will swing on its pivot in the manner indicated in Figure 6 while thus engaged with the belt. This operation tends to straighten the belt or bring it into proper 90 alinement. In the actual operation of the machine, the link swings back and forth several times before the belt is properly alined. Should the correcting movement given to one side of the belt be more than 95 is sufficient, the devices on the opposite side of the alining device will operate on the opposite edge portion of the belt and this operation of the devices on opposite sides of the belt will continue until the normal alinement 100 of the belt is obtained.

The alining devices for the inner belt are shown at O. These comprise links o' pivotally connected with the frame pieces C at o^2 . The links o' carry a roller o hereinbefore referred to corresponding with the roller u and these links also carry small rollers o^3 similar in all respects to the small rollers u^6 , u^7 and drawn towards the roller o by springs o^4 . The links o' extend upwardly 105 from the inclined frame bars C and hold the roller o , above these frame bars. The links are continued downward below the inclined frame bars and carry counterbalancing weights O^2 . These alining devices O 110 serve to preserve the proper direction of movement of the inner belt while the alining devices U preserve the proper direction of movement of the outer belt. These alining devices co-operate with each other and the 115 superimposed belts are thus caused to carry the prints properly from feeding position through the drying means to the point of delivery.

A machine constructed as shown in the 120 drawings and as hereinbefore described has been found to be most efficient in practice. The tension of the belts is automatically ad-

justed and remains uniform. The prints are delivered in a flat condition thoroughly dry. By placing the drying drums one above the other with a space between them the heat 5 from the lower drum assists in heating the upper drum, thus saving fuel. Furthermore the belts are dried to a material extent and the moisture evaporated therefrom and from the prints while they are passing between 10 the heated air space between the drums, as in this way considerable portions of the inner belts are exposed to the evaporating effects of the heated air.

By bending the belts towards each other 15 between the drums a larger amount of belt surface is brought into contact with the drums.

An important feature of the invention resides in the device for automatically 20 serving the alinement, as in this way the belts may be made to move continuously without dropping the prints and without becoming jammed in the guide mechanism.

I claim as my invention:

25 1. In a drier for photographic prints and the like, the combination of upper and lower heated drums, with an air space between them, a belt traversing both drums and a belt guide in the air space between the 30 drums for drawing the oppositely moving portions of the belt between the drums towards each other and thus increasing the amount of surface contact between the belt and the drums.

35 2. In a drier for photographic prints and the like, the combination of one or more heated drums, superimposed belts moving in contact therewith and adjustable means operating on the discharging ends of the 40 belts to bend them and to thus flatten or straighten prints delivered by the belts.

45 3. In a drier for photographic prints and the like, the combination of a heated drum, superimposed belts moving in contact therewith, guides for the receiving and discharging portions of the belts, intermediate guides for the belts, and an adjustable guide roller operating on the discharge portion of the belts to bend the same and to thus flatten 50 the prints contained between the belts.

55 4. A drier for photograph prints and the like, comprising a heated drum, superimposed belts traversing the drum, guides for the belts, and a tension device operating on the belts comprising a pivotally mounted frame, ratchet mechanism for adjusting it, rollers carried by the frame in contact with the belts, and a spring for holding the frame under tension.

60 5. In a drier for photographic prints and the like, the combination of heated drums arranged one above the other, superimposed belts traversing the drums, guides for the belts, and a belt tension device comprising a 65 roller held in contact with the belt, a frame

in which it is mounted, and a spring for holding the frame yieldingly.

6. In a drier for photographic prints and the like, the combination of heated drums arranged one above the other, endless superimposed belts moving in contact with the drums, guides for the belts, and a tension device engaging one of the belts comprising a pivotally mounted frame, a ratchet wheel rigidly secured thereto, rollers on the frame 70 engaging opposite sides of the belt, a pawl-carrying lever cooperating with the ratchet wheel, and a spring connected with the lever for holding the tension device yieldingly.

7. In a drier for photographic prints and the like, the combination of heating means, superimposed print-carrying belts moving in contact with the heating means, guides for the belts, and devices for maintaining 80 the alinement of the belts, one of which comprises a guide roller in contact with which the belt normally moves, and other smaller rollers adapted to engage the edge portions 85 of the belt on the opposite side thereof.

8. In a drier for photographic prints and the like, the combination of drying means, 90 an endless belt moving in contact with the drying means, guides for the belt, and means for maintaining the alinement of the belt comprising a guide operating on one side of the belt, and devices arranged on the opposite side of the belt and adapted to operate on the edge portions thereof to correct 95 the alinement.

9. In a drier for photographic prints and the like, the combination of drying means, a 100 belt cooperating therewith, guides for the belt, and means for maintaining the alinement of the belt, comprising a guide roller on one side of the belt, and devices operating on the edge portions of the opposite side 105 of the belt mounted to move back and forth lengthwise of the belt.

10. In a drier for photographic prints and the like, the combination of drying means, a 110 belt cooperating therewith, guides for the belt, and means for maintaining the alinement of the belt, comprising a roller engaging one side of the belt, small rollers on the opposite side of the belt and adapted to engage the edge portions thereof, and links pivotally mounted in the frame of the machine adapted to swing longitudinally of the belt while the belt is moving through the 115 machine.

11. In a drier, the combination of upper and lower heated drums with an air space between them, a belt traversing both drums and which is exposed to the air space between the drums when passing from one 120 drum to the other.

12. In a drier, the combination of a heated drum, a belt traversing the drum, guides for the belt, and a belt tension device comprising a roller held in contact with the belt, a 130

frame in which it is mounted, and a spring for holding the frame yieldingly.

13. The combination with a belt, guides therefor, means for moving the belt and 5 means for maintaining the alignment of the belt comprising a guide operating on one side of the belt and devices arranged on the opposite side of the belt moving longitudi-

nally therewith and adapted to operate on the edge portions of the belt to maintain 10 alignment.

In testimony whereof, I have hereunto subscribed my name.

WILBERT H. MORGAN.

Witness:

GEORGE J. BRIGHAM.
